UNITED STATES PATENT OFFICE

154,879

DESIGN FOR A FAUCET FOR DISPENSING CARBONATED BEVERAGES

John E. Rosander and Axel E. Rosander,
Minneapolis, Minn.

Application March 31, 1947, Serial No. 138,066

Term of patent 14 years

(Cl. D2—3)

To all whom it may concern:

Be it known that we, John E. Rosander and Axel E. Rosander, citizens of the United States, residing at Minneapolis, in the county of Hennepin and State of Minnesota, have invented a new, original, and ornamental Design for Faucets for Dispensing Carbonated Beverages, of which the following is a description, reference being had to the accompanying drawings, forming part thereof.

Figure 1 is a perspective view of a faucet for dispensing carbonated beverages, showing our new design;

Figure 2 is a side elevational view thereof; and Figure 3 is a front elevational view.

We claim:

The ornamental design for a faucet for dispensing carbonated beverages, as shown.

JOHN E. ROSANDER.
AXEL E. ROSANDER.
